UNITED STATES PATENT OFFICE.

HENRY E. KEYES, OF PHILADELPHIA, PENNSYLVANIA.

HAMMER.

Application filed October 7, 1922. Serial No. 592,981.

To all whom it may concern:

Be it known that I, HENRY E. KEYES, a citizen of the United States, residing at Philadelphia, in the county of Philadelphia and State of Pennsylvania, have invented 5 certain new and useful Improvements in Hammers, of which the following is a specification.

This invention relates to hammers provided with renewable faces; and it consists in the novel construction and combination of the parts hereinafter fully described and claimed whereby the striking face of the hammer is attached to the head.

In the drawings, Figure 1 is a side view of a hammer constructed according to this invention and showing a portion of it in section. Fig. 2 is a side view of a portion of the hammer head, partially in section and showing the face and jacket in a position to be connected to it. Fig. 3 is a longitudinal section through the face and its jacket detached from the head. Fig. 4 is an end view of the same. Fig. 5 is also a longitudinal section and shows a modification of the face and its jacket.

The hammer head 8 is formed of any suitable hard metal, and it has a handle 9 secured to it in any approved way. The hammer head preferably has a striking face 10 at each end, but as both are alike the description will be restricted to one end.

The hammer head 8 has a cylindrical projection 12 arranged in line with its axis, and having a circumferential groove 14 where it joins onto the head. A shoulder 13 is formed on the head around the projection, and this shoulder has a concave recess 15 which merges into the bottom of the groove 14. The striking face 10 of the hammer is preferably formed of soft material, lead or a similar soft and ductile metal being preferably used. In carrying out this invention the hammer face may be made 45 of lead, brass, copper, raw hide, fiber, and other soft materials.

When the face 10 is formed of lead, it is provided with a cylindrical shank 18 which has a cylindrical socket 19 which fits over the projection 12 on the hammer head. The shank is smaller in diameter than the face, so that a shoulder 20 is formed at their point of junction. Longitudinal lugs 21 are provided on the shank, and are arranged 55 at equal distances apart. A cylindrical steel jacket 22 incloses the shank 18, and

one end of it bears against the shoulder 20. The end portions of the lugs 21 project from the other end of the jacket, and the jacket is permanently secured to the shank.

The face is slid over the projection 12 as shown in Fig. 2. The ends of the lugs are then driven hard into the concave recess so that they are bent around into engagement with the groove 14, as shown in Fig. 1, thereby securing the striking face to the hammer head. When the striking face becomes worn out, it and its jacket are removed from the head in any convenient way, the jacket being preferably gripped in a vice, and the hammer head being twisted around until the lugs are bent and broken.

In the modification shown in Fig. 5 the lead shank 18' is formed separately from the striking face 10', and the steel jacket 22' is formed of increased length so that it secures the shank and face together. When made in this way the face 10' can be made of raw hide or other soft material which is not suitable for the fastening lugs of the shank.

When in use, the blows struck by the hammer do not loosen the striking face, as the blows only tighten the grip of the fastening lugs in the circumferential groove of the head.

The lead striking face with its shank and lugs is preferably cast into the steel jacket, and the projecting parts 23 of the lugs are made thicker than their main portions, which are encircled by the jacket, so that they will fit better and more tightly in the groove. The steel jacket prevents the lugs from bending outwardly.

What I claim is:

1. A hammer head provided with a shoulder and a projection undercut at the shoulder, and a detachable striking face provided with a socket which fits over the projection and which has a series of longitudinally projecting lugs of relatively soft and ductile material which are locked upon the said projection by impact against the said shoulder.

2. A hammer head provided with a projection, a circumferential groove, and a shoulder having a concave recess; and a detachable striking face provided with a shank having a socket which fits over the said projection, said socket having fastening lugs which are bent into engagement with the said groove by contact with the

bottom of the said recess and which bear against the said shoulder.

3. A hammer head provided with a projection, a detachable striking face provided with a shank having a socket which fits over the said projection and which has fastening lugs for securing it to the hammer head, and a jacket encircling the said shank and permitting the said lugs to engage with the head, said lugs being of relatively soft and ductile material and being locked over the said projection.

4. A hammer head provided with a projection, a circumferential groove, and a shoulder; a detachable striking face provided with a shank having a socket which fits over the said projection and which has fastening lugs for engaging with the said

groove, and a jacket inclosing the said shank and bearing against the said shoulder when the fastening lugs are interlocked with the groove and projection.

5. A hammer head provided with a projection, a circumferential groove, and a shoulder; a detachable striking face provided with a shank having a socket which fits over the said projection and which has fastening lugs provided with normally thickened end portions which engage with the said groove, and a jacket formed of harder material than the said lugs and inclosing the said shank and the main portions of the said lugs.

In testimony whereof I have affixed my signature.

HENRY E. KEYES.
